EAR RESPONSE COMPENSATED VOLUME
CONTROL APPARATUS

John M. Hanert, Park Ridge, Ill., assignor to
Hammond Instrument Company, Chicago, Ill.,
a corporation of Delaware

Application February 1, 1950, Serial No. 141,692

7 Claims. (Cl. 179—171)

1

This invention relates generally to apparatus for smoothly varying the tonal output of an electrical musical instrument with adequate compensation for variations in the response of the human ear to tones of different frequencies and different intensities.

This application is a continuation in part of my application for patent Serial No. 592,099 entitled Volume Control Apparatus filed in the United States Patent Office on May 5, 1945.

This application has been abandoned.

A volume or expression control for an electrical musical instrument should meet a number of requirements. It should be capable of smoothly and continuously changing the tonal output of the instrument over a wide dynamic range. It should be rugged enough to withstand hard use and even abuse throughout the life of the instrument without requiring replacement or servicing, other than routine maintenance. The control should be completely quiet in operation, both mechanically and electrically, throughout the life of the instrument. The control should compensate for the nonuniform frequency response characteristics of the human ear.

It is well-known that sounds having intensities less than a certain level, known as the threshold of audibility, are inaudible to the human ear. Moreover, sounds having intensities greater than a level, known as the threshold of pain, produce a sensation of pain in the ear in addition to sound. In an electrical musical instrument all useful variations of sound volume must be confined between the upper limit of the threshold of pain and the lower limit of the threshold of audibility.

It is also well-known that the threshold of audibility is at its lowest level for sounds having intermediate frequencies within the normal range of the human voice and that the level of the threshold increases for sounds of both higher and lower frequencies. Of course, very low frequency sounds such as those below about 16 C. P. S., and sounds of very high frequencies, such as those above about 20,000 C. P. S. are inaudible to most people. Furthermore, the level of the threshold of pain is somewhat higher for voice range frequencies than it is for relatively higher treble and lower bass frequencies.

The tones which may be produced by an electrical musical instrument, such as an electric organ, may extend over a very wide frequency range, from about 30 C. P. S. to about 10,000 C. P. S. for example. Such range includes, in addition to all the normal voice or intermediate fre-

2

quencies, a wide range of lower bass and higher treble frequencies. As generated, tone signals of all frequencies usually have approximately equal amplitudes. For moderately great volume levels it is musically satisfactory to sound tones of all frequencies at approximately equal intensities, and thus the volume control apparatus and the output system of the organ may have a flat frequency response for such volume levels. It is desirable, by means of the volume control, to reduce the tonal output of the instrument to the threshold of audibility without seriously disturbing the apparent balance among tones of various frequencies. Because of the relative insensitivity of the human ear to very low and very high frequency tones, the response of the volume control together with the output system should be considerably greater for such low and high frequencies than for intermediate or voice frequencies when the control is adjusted to provide a barely audible tonal output. It is especially important that even at very low volume levels the low frequency or bass tones be maintained at an audible level, because the bass tones, to an important extent, determine the over-all musical character of the tonal output of the instrument.

Since the human ear will tolerate greater intensities of intermediate or voice frequencies than of very low and very high frequencies, the highest possible useful volume may be obtained only if the volume control apparatus together with the output system attenuates very low bass and very high treble frequencies somewhat, so that the intensities of such frequencies do not exceed the threshold of pain when the control is adjusted for maximum volume. Therefore, the high treble and low bass responses of the volume control together with the output system should be somewhat smaller than the intermediate or voice frequency response when the volume control is adjusted for maximum volume.

Consequently an adequate volume control for an electrical musical instrument must have frequency response characteristics which change radically as the volume adjustment is changed. The bass response, and to a lesser extent the treble response, relative to the intermediate frequency response, should be boosted as the volume is reduced. Such volume control compensation is variously known as ear response compensation, bass compensation or bass boosting.

None of the known volume controls for electrical musical instruments satisfy all the above requirements. The principal object of this invention is to provide volume control apparatus

for an electrical musical instrument which satisfies these requirements.

Specifically, an object of this invention is to provide volume control apparatus which will produce smooth, continuous and step-free variation of the tonal output of an electrical musical instrument rather than volume variation in finite steps which has characterized many prior art volume controls.

A further object is to provide a volume control which will withstand long and hard service without requiring attention.

A further object is to provide a volume control which will operate quietly without producing electrical transients throughout the life of the instrument.

A further object is to provide volume control apparatus which has frequency response characteristics which change as the volume is varied in order to compensate for the nonuniform frequency and intensity response characteristics of the ear.

A further object of this invention is to provide such volume control apparatus which may readily be manufactured at low cost.

Other objects and advantages together with an understanding of the basic principles of this invention may be derived from the following description together with the drawings in which:

Figure 1 is a wiring diagram of an illustrative embodiment of this invention.

Figure 2 is an elevational sectional view, taken on the plane 2—2 of Fig. 3, of a variable capacitor forming a part of the illustrative embodiment.

Figure 3 is an elevational sectional view of the capacitor taken on the plane 3—3 of Fig. 2.

Figure 4 illustrates suitable apparatus for operation of the variable capacitor by means of an organ expression pedal.

Referring to Fig. 1, volume control apparatus is illustrated which is adapted to provide musical tone signals of variable amplitude from its output terminals 10 and 12 for transmission to the output system 16 of an electrical musical instrument in response to constant amplitude tone signals impressed upon input terminals 18 and 20 of the control apparatus by the musical tone signal generating system 22 of the instrument. The input terminal 20 is grounded while the input terminal 18 is connected with the control grid of a coupling pentode 24 by means of a radio frequency filtering resistor R26. The input terminals 18 and 20 are shunted by a grid resistor R28. The plate of the pentode 24 is connected with an anode voltage supply terminal +285 v. by means of a parallel mesh comprising a load resistor R30 and a small high frequency by-pass capacitor C32. An adjustable amount of negative feedback is provided by a small adjustable capacitor C34 connected between the plate of the pentode 24 and the input terminal 18. Further degenerative action is provided by an unbypassed cathode resistor R36 connected between the cathode of the pentode 24 and ground. The screen grid of the pentode 24 is connected with the +285 v. terminal by a resistor R38 and is by-passed to the cathode by a capacitor C40.

The pentode 24 serves as an amplifier and coupling tube and provides amplified tone signals corresponding with those supplied by the generating system 22. The anode of the pentode 24 is connected by a conductor 42 with a set of stationary plates 44 of a variable capacitor C46. A second set of stationary plates 48 is connected

with the anode of the pentode 24 by means of an ear response compensated attenuating mesh 50. The attenuator 50 may comprise a resistor R52 shunted by a capacitor C54 connected between the anode of the pentode 24 and a terminal 56, a capacitor C58 in series with a resistor R60 connected between the terminal 56 and ground, a resistor R62 in parallel with a capacitor C64 connected between the terminal 56 and the set of capacitor plates 48, a resistor R66 shunted from the set of capacitor plates 48 to ground and a capacitor C68 in series with a resistor R70 likewise shunted from the plates 48 to ground.

The mesh 50 attenuates high and low frequencies less than a middle range of frequencies. For middle range frequencies the mesh 50 provides two cascaded frequency selective voltage divider sections individually including a series arm and a shunt arm. The first series arm comprises R52 in parallel with C54 and the first shunt arm comprises C58 in series with R60. A signal voltage from the pentode 24 divides between the first series arm and the first shunt arm, and only the portion which develops across the shunt arm is transmitted to the second voltage divider. The series arm of the second voltage divider section comprises R62 in parallel with C64 and the second shunt arm comprises R66 in parallel with the series combination of C68 and R70. The signal voltage received from the first voltage divider section divides between the second series arm and the second shunt arm, and only the portion of the voltage across the second shunt arm is transmitted to the stationary plates 48 of C46.

For low bass frequencies the capacitive reactance of C58 is much larger than the resistance of R52 because the capacitive reactance of C58 increases as the frequency decreases. Therefore the attenuation of the first voltage divider section is very small for such low bass frequencies. Moreover the capacitive reactance of C68 is much greater than the resistance of R62 for low bass frequencies, and so the second voltage divider section attenuates low frequency signals much less than middle frequency signals. However, the shunting effect of R66 together with the series impedances of R52 and R62 provides some attenuation at low frequencies.

The capacitive reactance of C54 decreases as the frequency increases and becomes much less than the individual resistances of R52 and R60 to high treble frequency signals. Therefore the first voltage divider section attenuates high frequency signals relatively very little. Likewise the capacitive reactance of C64 for high frequency signals is much less than the individual resistances of R62, R70 and R66, and attenuation of high frequency signals by the second voltage divider section consequently is relatively small.

For the reasons explained above the mesh 50 attenuates low bass frequencies signals and high treble frequencies signals relatively much less than middle frequency range signals. C54 and C64 permit high frequency signals to pass to the capacitor plates 48 of the C46 with little attenuation. For low bass frequencies the impedances of the shunt arms of the mesh 50 are relatively very high because of the high reactances of C58 and C68, and low bass frequency signals consequently pass to the plates 48 through R52 and R62 with little attenuation.

The variable capacitor C46 includes a set of

scanner plates 74 which is movable into capacitive pickup relation with either of the sets 44 and 48 of stationary plates or partially in any selected ratio into capacitative relation with said sets of plates. The scanner plates 74 are connected with the grid of a phase inverter triode 76 which may be one unit of a double triode tube as illustrated. A capacitor C82 shunted by a grid return resistor R84 connects the scanner plates 74 with a terminal 78 which is by-passed to ground by a large bias filter capacitor C80. The terminal 78 is connected directly to the grid of a second phase inverter triode 86 and is connected by a resistor R88 with a positively charged grid bias source terminal +20 v. The cathodes of the triodes 76 and 86 are connected to ground by a high resistance common cathode biasing resistor R90. The anodes of the triodes 76 and 86 are connected with an anode supply terminal +290 v. by individual anode load resistors R92 and R94 respectively, and with the output terminals 10 and 12 by individual coupling capacitors C96 and C98 respectively. The output terminals 10, 12 are connected with the output system 16 which may include, for example, a power amplifier and a speaker (not shown).

According to their position, the scanner plates 74 pick up signals from either the stationary plates 44 or 48 or from both sets of plates 44 and 48 jointly in any selected proportion, and the signals are impressed upon the grid of the triode 76. Resistor R84 provides a direct current path from the grid of the triode 76 to ground through R88 and the grid bias source and also may slightly modify the low frequency response of the volume control apparatus together with the amplifiers and the output system 16. C82 may have a capacitance such that its capacitive reactance at the lowest frequency which is to be transmitted by the apparatus is of the same order as the resistance of R84, and so for intermediate and high frequencies the capacitive reactance of C82 is much less than the resistance of R84. Thus for intermediate and high frequencies the shunting effect of R84 is negligible and the capacitive voltage divider comprising C46 and C82 has a uniform frequency response for such intermediate and high frequencies. At the lowest frequencies to be transmitted, however, the shunting effect of R84 may produce some attenuation. The capacitance of C80 is great so that even at the lowest frequency to be transmitted its capacitive reactance is negligible relative to the resistances of R84 and R88, and so the terminal 78 is maintained nearly at ground potential for signal voltages. C80 is provided primarily to filter out any ripple components present in the +20 v. bias supply voltage.

The triodes 76 and 86 provide phase inversion and amplification. Signals develop across the high resistance common cathode resistor R90 which have amplitudes about one-half the amplitudes of the signals impressed upon the grid of the triode 76 by the scanner plates 74. Since the grids of both triodes 76 and 86 are returned to the terminal 78 which is at ground potential for signal voltages, the signals across R90 appear in the grid-cathode circuits of both triodes 76 and 86, providing negative feedback for the triode 76 and reversely phased input signals for the triode 86. The grids of the triodes 76 and 86 are returned to the positive grid bias source terminal +20 v. in order to counteract part of the excessively great negative grid bias provided by the voltage drop across R90 and thus to provide a suitably small negative grid-cathode bias for the

triodes 76 and 86. Output voltages which are approximately balanced with respect to ground are provided by R92 and R94 and are coupled to the output system 16 through C96 and C98.

5 The mechanical details of the variable capacitor C46 are illustrated in Figs. 2 and 3. The scanner plates 74 are mounted on a bracket 100 secured to an insulating plate 102 which is mounted on a rotatable shaft 104 by means of a U-shaped arm 106 secured to a hub 108. A set screw 110 which engages the shaft 104 permits longitudinal adjustment of the hub 108 along the shaft 104 over a limited range. A control arm 112 is secured to the end of shaft 104 by means of a bushing 114. Suitable bearings 111 and 113 mounted on a housing 115 support the shaft 104. Longitudinal movement of the shaft is prevented by a set screw collar 117.

20 The stationary plates 44 and 48 are secured by brackets 118 and 120 respectively to an insulating base plate 122 secured to the housing 115.

25 The adjustable capacitor C34 is mounted on a partition 124 within the housing 115. An electrical connection is made to the scanner plate 74 by means of a flexible wire (not shown) connected with a soldering lug 126. Connections with the stationary plates 44 and 48 are made to soldering lugs 128 and 130 respectively. The housing 115 is normally grounded to provide 30 shielding for the variable capacitor C46 and the adjustable capacitor C34.

35 The full line position of the scanner plates 74 and the control arm 112 is the minimum volume setting with the scanner plates 74 meshed with the stationary plates 48, while the dotted line position of the scanner plates 74 and the control arm 112 is the maximum volume setting with the plates 74 meshed with the stationary plates 44. The scanner plates 74, together with the 40 control arm 112, are continuously movable between these extreme positions so as to mesh partially with both sets of stationary plates 44 and 48 in any desired proportion.

45 In Fig. 4 the variable capacitor C46 is mounted within a console 134 of an electrical musical instrument having an expression pedal 136 pivotally mounted at the front of the console 134. A linkage rod 138 pivotally connected with the control arm 112 and with a bracket 140 mounted on the pedal 136 provides an operating connection between the pedal 136 and the control arm 112. The pedal 136 may be tilted between limits defined by a front stop 142 and a rear stop 144. When the pedal 136 is in its full line position against the front stop 142 the linkage rod 138 moves the control arm 112 so that the variable capacitor C46 is in its minimum volume position, and when the pedal 136 is in its dotted line position against the rear stop 144 the control arm 112 is moved to its maximum volume position by the linkage rod 138.

60 When full volume is desired the musician tilts the expression pedal 136 to its dotted line position against the rear stop 144, thus moving the scanner plates 74 into the dotted line position (Fig. 3) in capacitative pickup relation with the stationary plates 44. Referring to Fig. 1, tone signals will then be transmitted through the coupling pentode 24 and the conductor 42 to the stationary plates 44 and thence by capacity coupling to the scanner plates 74, the grid of the triode 76 and finally to the output system 16. The components of the apparatus in Fig. 1, including the generating system 22 and the output system 16, are so proportioned that a direct

connection by the conductor 42 from the plate of the pentode 24 to the stationary plates 44 provides frequency response characteristics suitable for a high volume level. Very low frequencies may be attenuated somewhat by the shunting effect of R84 while very high frequencies may be attenuated by the shunting effect of C32, and the response for intermediate frequency signals may be somewhat greater than for high and low frequency signals. In some cases it may be desirable to modify the frequency response characteristics at high volumes by providing a suitable filter, which may be in series with the conductor 42.

When a musician desires a minimum volume level he tilts the expression pedal 136 to its full line position against the front stop 142 so that the scanner plates 74 are moved into capacitative pickup relation with the stationary plates 48. Tone signals then are transmitted through the attenuating mesh 50 to the stationary plates 48 and thence capacitively coupled to the scanner plates 74. The attenuator 50 has signal transmission frequency characteristics suitable for maintaining a proper balance among tones of different frequencies at a low volume level. For example, the attenuating mesh 50 may attenuate signals of intermediate or voice frequencies by about 30 decibels (db), while attenuating very low frequencies only about 6 db and very high frequencies only about 10 db. Such an attenuator 50 together with the other components of Fig. 1 compensates approximately for the non-uniform frequency response characteristics of the human ear by boosting the high treble and low bass responses of the volume control apparatus to relatively higher levels than the intermediate frequency response at low volume levels. Consequently, bass tones and high treble tones are maintained at audible levels even when the overall volume of the tonal output of the instrument is at a minimum.

When intermediate volume levels are desired the expression pedal 136 is tilted to some suitable position between its full and dotted line positions in Fig. 4, thus moving the scanner plates 74 into capacitative pickup relation with both sets of stationary plates 44 and 48 jointly in any selected proportion. One such position of the scanner plates is illustrated in Fig. 1. Tone signals then are capacitively coupled to the scanner plate 74 from both sets of stationary plates 44 and 48, and the volume control has intermediate frequency response characteristics. If the scanner plates 74 are moved smoothly from their dotted line position in Fig. 3 to their full line position the signal transmission characteristics change smoothly as the volume decreases smoothly from maximum to minimum.

Since there are no sliding or rolling contacts in the volume control apparatus, complete freedom from noisy operation is assured for the life of the instrument. The volume control apparatus is simple, trouble-free, rugged and inexpensive. It will be apparent to those skilled in the art that volume control apparatus according to this invention meets all the requirements for service as an expression control in an electrical musical instrument.

In order to facilitate the practice of this invention, illustrative values of the components employed in the embodiment illustrated in Fig. 1 are tabulated below. These illustrative component values are given in order that the disclosure of this invention may be complete and specific.

The specific illustrative values set forth should not be construed to limit the scope of this invention because those skilled in the art will understand that the values of the components may be varied over a considerable range without departing from the basic principles of this invention. A complete statement of the true scope of this invention will be found in the appended claims.

The capacitance between the plates 44 and 74, as well as between plates 48 and 74, when the plate 74 is in registry with either of these plates, may be exceedingly low, in the order of 25 micro-microfarads. Thus the scanner plate 74 is effective solely as a means for smoothly varying the over-all dynamic response, as well as the over-all frequency response, from a point of high volume when plate 74 is in registry with plate 44, to an extreme of low volume when plate 74 is in registry with plate 48. It is to be noted that when 74 is partially in registry with both 44 and 48 an intermediate over-all intensity and frequency response curve results.

In the following table the values of resistors are given in ohms, thousands of ohms (K), or megohms (meg.). Values of capacitors are given in microfarads.

30	R26	-----	.33 meg.
	R28	-----	5.6 meg.
	R30	-----	.27 meg.
	C32	-----	.0002
	C34	-----	.000015
35	R33	-----	1500 ohms
	R38	-----	1.5 meg.
	C40	-----	.25
	R52	-----	1.8 meg.
	C54	-----	.0002
	C58	-----	.002
40	R59	-----	68K
	R63	-----	1.8 meg.
	C64	-----	.0002
	R66	-----	5.6 meg.
	C68	-----	.001
45	R70	-----	68K
	C80	-----	.25
	C82	-----	.0005
	R84	-----	5.6 meg.
	R88	-----	.18 meg.
50	R90	-----	39K
	R92	-----	.47 meg.
	R94	-----	.47 meg.
	C96	-----	.05
	C98	-----	.05

A specific illustrative embodiment of this invention has been described in order that those skilled in the art may readily understand the fundamental principles of this invention. However, those skilled in the art will be able to apply the principles disclosed herein to provide structures which may differ in their details from the specific embodiment described herein. Therefore the scope of this invention should not be limited by the details of the above disclosure except as set forth in the appended claims which are intended to include such modifications and equivalents which are within the true scope of this invention.

I claim:

1. In an electrical musical instrument including a tone signal generating system having an output and an output system having an input; volume control apparatus, including first and second adjacent capacitor plates, a scanner plate relatively movable to be in capacitative pickup

relation with either of said first or second plates, or partially in any selected ratio in capacitative relation with said plates, means coupling said first plate with the output of said generating system, said means having frequency response characteristics suitable for a maximum volume by attenuating the low bass frequencies to a greater extent than the medium treble frequencies, attenuating means coupling said second capacitor plate with the output of the generating system, said attenuating means having frequency response characteristics suitable for a minimum volume by attenuating intermediate voice frequencies to a much greater extent than the bass and higher treble frequencies, and means coupling said scanner plate with the input of the output system, whereby compensation is made for the nonuniform frequency response characteristics of the ear.

2. An ear response compensating volume control for an electrical musical instrument, comprising an input terminal, first and second adjacent stationary capacitor plates, a scanner plate relatively movable into capacitative pickup relation with either of said plates or partially in any selected ratio into capacitative pickup relation with both of said plates, signal transmission means coupling said first capacitor plate with said input terminal, attenuating means coupling said second capacitor plate with said input terminal, said attenuating means providing substantially greater attenuation of signals in the voice frequency range than of low frequency signals, an output terminal, and means coupling said scanner plate with said output terminal.

3. In an electrical musical instrument, a source of tone signals, first and second capacitor plates, signal transmission means coupling said first plate with said source, an attenuator mesh providing substantially greater attenuation in the intermediate voice frequency range than said signal is attenuated by the transmission means coupling said second plate with said source, a scanner plate relatively movable into capacitative coupling relation with either of said first and second plates or partially in any selected ratio with both of said first and second plates, substantially capacitive load impedance means connected with said scanner plate, an output system, and a means coupling said scanner plate with said output system.

4. In an electrical musical instrument, a pair of output terminals of a source of a plurality of tone signals including voice frequency range signals as well as lower bass frequency signals and higher treble frequency signals, first and second capacitor plates, signal transmission means connecting said first plate with one terminal of said source, an attenuator mesh having substantially greater attenuation than said signal transmission means coupling said second plate with the same terminal of said source, the difference in signal attenuating characteristics between said signal transmission means and said attenuator mesh being greater for said voice frequency range signals than for said lower bass frequency and higher treble frequency signals, a scanner plate relatively movable into capacitative coupling relation with either of said first and second plates or partially in any selected ratio with both of said first and second plates, an output system including an electron discharge device having a control grid and cathode, means connecting said scanner plate with said control

grid, means connecting said cathode to the other terminal of the source, and a low value capacitor connected between the control grid and cathode, whereby the balance among tone signals of various frequencies is changed as the output volume is changed by moving said scanner plate, to compensate for the nonuniform frequency response characteristics of the human ear.

5. In an electrical musical instrument, a source of a plurality of tone signals including voice frequency range signals as well as lower bass frequency signals and higher treble frequency signals, first and second capacitor plates, signal transmission means coupling said first plate with said source, an attenuator mesh having substantially greater attenuation than said signal transmission means coupling said second plate with said source, the difference in the signal attenuating characteristics of said signal transmission means and said attenuator mesh being substantially less for said bass frequency signals than for said voice frequency range signals, a scanner plate relatively movable into capacitative coupling relation with either of said first and second plates or partially in any selected ratio with both of said first and second plates, an output system, and means coupling said scanner plate with said output system, whereby the balance among tone signals of various frequencies is changed as the output volume is changed by moving said scanner plate to compensate for the nonuniform frequency response characteristics of the human ear.

6. In an electrical musical instrument, a source of a plurality of tone signals including voice frequency range signals as well as lower bass frequency signals and higher treble frequency signals, first and second capacitor plates, signal transmission means coupling said first plate with said source, an attenuator mesh having substantially greater attenuation than said signal transmission means coupling said second plate with said source, the difference in signal attenuating characteristics between said signal transmission means and said attenuator mesh being less for said treble frequency signals than for said voice frequency range signals, a scanner plate relatively movable into capacitative coupling relation with either of said first and second plates or partially in any selected ratio with both of said first and second plates, an output system, means coupling said scanner plate with said output system, and additional means for attenuating the higher treble frequencies and the lower bass frequencies in the signals transmitted from the source to the output system irrespective of the position of the scanning plate, whereby the balance among tone signals of various frequencies is changed as the output volume is changed by moving said scanner plate, to compensate for the nonuniform frequency response characteristics of the human ear.

7. In an electrical musical instrument, a source of a plurality of tone signals including voice frequency range signals as well as lower bass frequency signals and higher treble frequency signals, an output system, a high volume path coupling said source with said output system, a low volume path coupling said source with said output system, an ear response compensated attenuator forming a part of said low volume path for compensating for the nonuniform response characteristics of the ear by attenuating medium voice frequencies to a greater extent than the

11

higher treble and lower bass frequencies are attenuated, and a variable capacitor forming a part of said high volume path to vary the transmission of signals through said high volume path relative to said low volume path, whereby the balance among tone signals of various frequencies is changed as the output volume is changed by adjusting said capacitor in order to compensate for the nonuniform response characteristics of the human ear.
